COMBINED CAN OPENER AND MEASURING CUP

Alyce L. Bird, Mission, Kans.

Application September 15, 1955, Serial No. 37,946

Term of patent 14 years

(Cl. D44—29)

Fig. 1 is a perspective view of the combined can opener and measuring cup, showing my new design;

Fig. 2 is a perspective view thereof showing the inside of the measuring head and grip;

Fig. 3 is a side elevational view thereof showing the side opposite that shown in Fig. 1;

Fig. 4 is an end elevational view; and

Fig. 5 is a cross-sectional view thereof taken on line V—V of Fig. 2.

I claim:

The ornamental design for a combined can opener and measuring cup, as shown.
